(57) **CLAIM**

The ornamental design for a street litter bin, as shown and described.

DESCRIPTION

FIG. 1 is a front, left and top perspective view of a street litter bin, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of a second embodiment of a street litter bin.

FIG. 10 is a rear, left and top perspective view of the second embodiment of the street litter bin of FIG. 9.

FIG. 11 is a front elevation view of the second embodiment of the street litter bin of FIG. 9.

FIG. 12 is a rear elevation view of the second embodiment of the street litter bin of FIG. 9.

FIG. 13 is a left side elevation view of the second embodiment of the street litter bin of FIG. 9.

FIG. 14 is a right side elevation view of the second embodiment of the street litter bin of FIG. 9.

FIG. 15 is a top plan elevation view of the second embodiment of the street litter bin of FIG. 9; and,

FIG. 16 is a bottom plan elevation view of the second embodiment of the street litter bin of FIG. 9.

The broken lines depict portions of the street litter bin that form no part of the claimed design.

1 Claim, 16 Drawing Sheets
